UNITED STATES PATENT OFFICE.

CARLOSTIN C. FERRY, OF HILLSBOROUGH, ASSIGNOR OF ONE-HALF TO
ROSTO O. WOOD, OF MANCHESTER, NEW HAMPSHIRE.

SPRING-BED.

SPECIFICATION forming part of Letters Patent No. 377,377, dated February 7, 1888.

Application filed April 21, 1887. Serial No. 935,711. (No model.)

To all whom it may concern:

Be it known that I, CARLOSTIN CYRUS FERRY, of Hillsborough, county of Hillsborough and State of New Hampshire, have invented a new and useful Improvement in Spring-Beds; and I hereby declare the following to be a full, clear, and exact description thereof, reference being had to the drawings which form a part of this specification, in which—

10 Figure 1 is a sectional plan view of my invention, showing the head portion of the bed elevated to an inclined position. Fig. 2 represents a plan view of the piece containing the tooth-rack and groove combined, for purposes hereinafter explained. Fig. 3 shows a metallic groove for purposes further on explained and in what manner applied.

15 The object of this invention is to provide a suitable mechanism for raising or lowering the head portion of a spring-bed to change the position of an invalid at pleasure without the aid of chairs or other support, as now resorted to, and in such a manner that no part of the bed-spring-frame support shall be weakened but 20 strengthened instead at a point where most needed.

It consists in attaching to the main frame-support a projection of hard wood or iron, preferably the latter, on which may be formed 25 ratchet-teeth in a horizontal position, and at right angles with which is a groove with or without a slot on its posterior surface for bolt-head, if desired, both of which I prefer to have cast in one piece, (but may be otherwise,) the 30 tooth-rack to receive a pawl and the grooves to receive end pins, friction-rollers, or bolts for purposes hereinafter explained and in what manner employed.

35 A' represents one of the longitudinal supporting-bars of a spring-bed, upon which the springs are placed. The pieces B are made about two feet in length parallel with each other, and held firmly in position by means of cross-slats or iron rods. On this frame so made 40 rest about one-third of the springs used for the bed. To the external perpendicular surface of pieces B, I attach a piece of hard wood or metal, in which is a groove for the reception of a metal pin, friction-roller, or bolt. (Seen at C.) (See 45 Fig. 2.) The pin, friction-roller, or bolt is

made a fixture at one end of lever D, and at the other end there is a similar pivot or bolt working in another groove at right angles with the horizontal tooth-rack, both of which—*i. e.*, tooth-rack and groove—are represented in one 55 piece and fastened to longitudinal bar A'.

D is a lever pivoted to link G at points *h* intermediate between pivots or bolts *a* and *f*, which operate within the grooves made fast to the external surface of longitudinal bars A' and B, respectively. The links G are pivoted to the longitudinal bar A' at one end and to the supplemental bar B at the other. If iron rods are used to connect the bars B, their ends may be used as pins to engage with the metallic 65 grooves, if desired.

On the pivot or bolt at the lower end of lever D, I place thereon loosely a pawl, K, which engages with the horizontal tooth-rack when the head portion of the bed is being raised, and 70 the pawls K or ratchet-clicks must necessarily work simultaneously and easily without the necessity of any connecting "cross-piece" or weight of any kind whatever, because, being fitted loosely upon the pivot or bolt, they must 75 of their own weight fall into place as they are drawn over the tooth-rack while the section is being raised.

Another way to combine a groove with the horizontal tooth-rack would be to place a 80 groove below the tooth-rack on one or both sides thereof and at right angles therewith, presenting a similar appearance to a T-rail with tooth-rack on top, and allow a projecting flange or flanges on the pawl or ratchet-click 85 to engage therein, and it will work equally as well for all practical purposes and with no extra expense.

I am aware that one Charles D. Rodebaugh obtained Letters Patent on a somewhat similar 90 device to my own for raising the head portion of a spring-bed; but in his device the grooves were chiseled out of the longitudinal bar or section-support, thereby weakening them to such a degree that several have been broken 95 while attempting to adjust the head portion of the bed in position, besides much valuable time is wasted in digging out those slotted grooves, and withal there is too much friction on the pivot or bolt working therein for all prac- 100

tical purposes in its adjustment; and, too, he attaches a cross-piece to the upper portion of the "dogs" (pawls) for the purpose, as he says, "to operate the two simultaneously on the horizontal tooth-rack," and I make no claim to his device or any part thereof.

What I do claim, and desire to secure by Letters Patent, is—

1. A horizontal tooth-rack and groove fastened to the external surface of the longitudinal bars A' and B of the frame-support, in combination with pivots or bolts *a* and *f*, pawls K, levers D, links G, the whole operating substantially in the manner and for the purposes herein described.

2. The combination of a combined horizontal tooth-rack and groove provided with slot on its posterior surface for bolt-head, with longitudinal bars of a frame-support of a spring-bed, and supplemental section thereof with groove attachment, pawl K, levers D, and links G, as and for the purposes herein described and set forth.

CARLOSTIN C. FERRY.
